United States Patent

Des. 235,938
Patented July 22, 1975

235,938

SAFETY CAP

Frank W. Lindblom, Warwick, R.I., assignor to
Textron Inc., Providence, R.I.

Filed June 27, 1973, Ser. No. 373,975

Term of patent 14 years

Int. Cl. D2—03

U.S. Cl. D2—231

FIG. 1

FIG. 2

FIG. 3

FIG. 4

FIG. 5

FIG. 6

FIG. 1 is a perspective view of a safety cap showing my new design;

FIG. 2 is a side view thereof;

FIG. 3 is a front view thereof;

FIG. 4 is a rear view thereof;

FIG. 5 is a top view thereof; and

FIG. 6 is a bottom view thereof.

I claim:

The ornamental design for a safety cap, substantially as shown.
